MEANS FOR SPLITTING PIPE COLLARS IN SITU

Walter T. Wells, Glendale, Calif., assignor to The Technicraft Engineering Corporation, Los Angeles, Calif., a corporation of California

Application July 14, 1934, Serial No. 735,213

9 Claims. (Cl. 81—183)

My invention relates to a means and method of splitting pipe collars in situ, and the objects of my invention are:

First, to provide a means of this class which is particularly designed for use in deep wells when it is desired to disconnect a tubing string at some point intermediate its ends, and which insures the disconnection of the tubing string at the desired point;

Second, to provide a means of this class which minimizes the need of rotating the tubing string and the attendant danger of unscrewing the same at some undesired point;

Third, to provide a means of this class which reduces to a minimum the damage to the tubing string and any surrounding casing;

Fourth, to provide a means and method of this class which utilizes gun fire controlled from the mouth of the well to split the pipe collars;

Fifth, to provide a means of this class which may be readily and quickly positioned in accurate relation with the collar to be split;

Sixth, to provide a method of splitting pipe collars in situ which may be readily and quickly carried out, and

Seventh, to provide a means of this class which may be readily and quickly withdrawn upon completion of the intended operation.

With the above and other objects in view as may appear hereinafter reference is made to the drawings, in which:

Figure 1 is an elevational view of my pipe collar splitting means in its extended position with its supporting cable shown fragmentarily; Figure 2 is a longitudinal sectional view thereof taken through 2—2 of Figure 1, with a tubing string coupling shown in relation therewith; Figure 3 is a partial sectional partial elevational view thereof similar to Figure 2 but showing the means in its retracted position; Figure 4 is a transverse sectional view through 4—4 of Figure 1 with a positioning spring shown in elevation; Figure 5 is an elevational view of a tubing string collar as it appears upon being split.

Figure 6 is an elevational view of a modified form of my means for splitting pipe collars; Figure 7 is a longitudinal sectional view thereof taken through 7—7 of Figure 6 and showing the tubing string in relation therewith; Figure 8 is a fragmentary sectional view showing one of the positioning springs in its extended position and taken substantially through 8—8 of Figure 12; Figure 9 is a fragmentary partial sectional partial elevational view of the means and surrounding tubing string in the position and condition occur-

ring upon splitting the pipe collar; Figure 10 is a fragmentary sectional view similar to Figure 8 showing one of the positioning springs in its retracted position; Figure 11 is a transverse sectional view through 11—11 of Figure 7 with the tubing string omitted; Figure 12 is another sectional view through 12—12 of Figure 7.

My means and method of splitting pipe collars may be used in conjunction with any of the inner tubing strings or well casings or even the outer casing of wells in some instances. Shown in conjunction with my means are two fragmentary sections of pipe, designated A, threaded at their adjacent ends and joined by a coupling B.

Attention is first directed to Figures 1 to 5 inclusive wherein is shown a cylindrical body member 1 the lower end of which is provided with a relatively large recess or chamber 1a into the lower end of which fits a bottom or guide plug 2. The plug 2 has a relatively large opening 2a therethrough and the lower portion of the chamber is provided with laterally directed ports 1b.

The chamber 1a receives a plunger 3. A plurality of positioning springs 4 are suitably secured to the plunger 3 and extend upwardly along the sides thereof and within the chamber 1a. Said chamber is provided with upwardly and outwardly directed slots 1c which form guides for the several positioning springs 4. The springs 4 and slots 1c are so arranged that when the plunger 3 is in its upper position the springs 4 curve outwardly and upwardly to engage the walls of the pipe A and to spring against the collar B as they pass. In this position the springs allow the body member to move downwardly past the collars but engage a shoulder, designated C, formed at the lower extremity of an upper pipe section upon withdrawing the body member. In their retracted position when the piston is in its lower position the springs 4 are within the chamber 1a and are adapted to engage a recess 1d provided therein, as shown in Figure 3.

The upper end of the body member 1 receives a cap member 5 which is secured in any suitable manner to a cable 6. Said cable includes a centrally disposed insulated conductor 6a.

Above the chamber the body member 1 is provided with a recess of smaller diameter intersecting its upper end and closed there by a plug 7 to form a chamber 1e. Said chamber receives a cartridge 8 having a filament 8a extending therethrough which is arranged in a circuit with the conductor 6a so as to be heated to incandescence and ignite an explosive packed within the cartridge.

The chamber $1e$ is intersected by a laterally directed bore $1f$ which receives a projectile 9 . The bore $1f$ is provided with a suitable sealing means 10 at its extremity. The chamber $1e$ is 5 also intersected by a port $1g$ which is directed towards the piston chamber $1b$ and controlled by a check valve means 11 to prevent the entrance of fluid into the chamber $1e$.

Operation of the above described structure is as 10 follows:

The means is lowered in the tubing or casing 15 slightly beyond the desired joint then withdrawn until the positioning springs engage the shoulder C . The projectile is then positioned to fire 20 through the upper section of pipe and coupling. The cartridge is then ignited by any suitable means causing the projectile to penetrate said pipe section and coupling. In doing so the wedge shaped point of the projectile splits the coupling 25 substantially as shown in Figure 5, whereupon the sections of pipe above the split coupling may be withdrawn by a direct upward movement perhaps assisted by a slight turning action. Inasmuch as the coupling is split, even though it 30 should still hold against axial movement the pipe may be rotated with assurance of unscrewing at this point, as the other undamaged joints in the tubing string offer greater resistance.

Upon firing the projectile, part of the energy 35 is directed through the port $1g$ to force the plunger 3 downwardly so as to withdraw or retract the positioning springs. If the pipe contains a liquid, said liquid is displaced through the ports $1b$ and opening $2a$.

The structure illustrated in Figures 6 to 12 40 differs over the above described structure principally in that spring means is provided for shifting the plunger, the spring means being restrained by a severable member traversing the path of the projectile.

A body member 12 is provided which is generally similar to the body member 1 having a recess or chamber $12a$ extending upwardly from its lower end, the recess receiving a plug 13 . 45 Ports $12b$ are provided in the chamber $12a$ and the plug 13 is likewise ported. The chamber $12a$ receives a plunger 14 which carries a plurality of positioning springs 15 positioned along the sides thereof and directed through slots $12c$ so as to 50 engage the shoulder C and to be locked in a retracted position by a recess formed within the chamber $12a$, as in the first described structure.

The plunger 14 is cup shaped and receives a spring 16 which bears against the upper end of 55 the recess or chamber $12a$ to urge the plunger downwardly and thereby retract the positioning springs 15 .

Above the chamber $12a$, the body member 12 is provided with a laterally directed socket the 60 inner portion of which receives a cartridge 17 and the outer portion of which is enlarged and screw threaded to receive a short gun barrel 18 . A sealing and fire delaying plate 19 is secured 65 between the gun barrel 18 and the cartridge 17 and additional yieldable sealing means may be provided.

The body member is provided with a cap member 20 which is suitably connected with a cable 21 carrying an insulated conductor $21a$ adapted 70 to be connected with the cartridge. The cartridge 17 is constructed similarly to the cartridge 8 .

The gun barrel 18 receives a projectile 22 and the outer end of its bore may be closed by a 75 sealing plate 23 .

The plunger 14 is held in its upper position by a catch arm 24 which is secured to the side of the body member in a slight recess and depends so as to traverse the mouth of the gun barrel. The lower end of the arm 24 has a tooth $24a$ 5 which fits into a slot formed in the side of the body member and a registerable recess provided in the side of the plunger.

Operation of the above described structure is 10 as follows:

The structure is lowered, positioned and fired in the manner of the first described structure. However, the projectile severs the catch arm 24 and at the same time forces the tooth $24a$ clear of its socket whereupon the plunger is forced to its 15 lower position by the spring 16 . Also in the last described structure greater velocity is given the projectile by reason of the plate $1a$ which must first be ruptured; although the cartridge E of the first described structure may have a metal jacket 20 to function in the same manner as the plate $1a$.

My method of splitting pipe collars in situ consists in lowering a projectile firing gun into the pipe to be disconnected, locating a particular connection, positioning the gun in a predetermined relation with the connection so as to fire through the surrounding collar, then electrically discharging the gun to drive a wedge shaped bullet through the collar and split the same.

I claim:

1. A means of splitting pipe collars in situ comprising; a device insertable in a pipe line for locating internally a collar connected joint; and a gun unit connected with said device for firing a splitting projectile through said collar; and 35 mechanism for rendering said device inoperative to facilitate removal of said device and gun unit.

2. A means of splitting pipe collars in situ comprising; a body structure adapted to be lowered in a pipe string; a device carried by said body structure for locating internally a collar connected joint; and a gun unit also carried by said body structure and positioned relative to said device to fire a projectile through the collar located thereby; and means for rendering said device inoperative upon firing of said gun unit.

3. A means of splitting pipe collars in situ comprising; a device insertable in a pipe line for locating internally a collar connected joint; explosive actuated collar splitting means positioned 50 in proximity to said device; and an instrumentality responsive to the said collar splitting means to render said device inoperative.

4. A means of splitting pipe collars in situ comprising; a body structure adapted to be lowered in 55 a pipe string; a plunger carried thereby; a plurality of positioning fingers carried by said plunger and shiftable thereby from an extended or engaging position with the interior of a collar connected joint to a retracted or inoperative 60 position; a gun unit carried by said body structure in proximity to said plunger arranged to fire a projectile through a collar located by said positioning fingers; and means for retracting said fingers upon firing of said gun unit.

5. A means of splitting pipe collars in situ comprising; a body structure adapted to be lowered in a pipe string; a plunger carried thereby; a plurality of positioning fingers carried by said 70 plunger and shiftable thereby from an extended or engaging position with the interior of a collar connected joint to a retracted or inoperative position; an explosive actuated means arranged to exert a splitting pressure upon said collar; and 75

means for retracting said fingers to facilitate withdrawal of said body structure upon discharge of said explosive actuated means.

6. A means of splitting pipe collars in situ comprising; a body structure adapted to be lowered in a pipe string; a plurality of positioning fingers carried by said body structure arranged to engage the interior of a collar connected joint; a gun unit carried by said body structure in proximity to said positioning fingers and arranged to fire a projectile through a collar located by said fingers; and means for retracting said fingers upon firing of said gun unit.

7. A means of splitting pipe collars in situ comprising; a body structure adapted to be lowered in a pipe string; a plurality of positioning fingers carried by said body structure arranged to engage the interior of a collar connected joint; an explosive actuated means carried by said body structure in proximity to said positioning fingers and arranged to exert a splitting pressure upon said collar; and means for retracting said fingers to facilitate withdrawal of said body structure upon discharge of said explosive actuated means.

25 8. A means for splitting pipe collars in situ com-

prising; a body structure adapted to be lowered in a pipe string; a plurality of positioning fingers carried by said body structure arranged to engage the interior of a collar connected joint; an explosive actuated means carried by said body structure in proximity to said positioning fingers and arranged to exert a splitting pressure upon said collar; and means for retracting said fingers.

9. A means of splitting pipe collars in situ comprising; a body structure adapted to be lowered in a pipe string; a plurality of positioning fingers carried by said body structure arranged to engage the interior of a collar connected joint; an explosive actuated means carried by said body structure in proximity to said positioning fingers and arranged to exert a splitting pressure upon said collar, said explosive actuated means comprising a cartridge within said body structure, a lateral bore extending from said cartridge and directed towards a collar located by said fingers, a fluid excluding seal initially closing the outer end of said bore, and a projectile within said bore; and means for retracting said fingers.
